CIGARETTE MAKER AND HOLDER

Max Friedman, High Point, N. C.

Application August 5, 1938, Serial No. 223,307

4 Claims. (Cl. 131—23)

This invention relates to a cigarette maker and holder and has for an object to provide an improved cigarette maker and holder of the type generally shown in U. S. Patents Nos. 52,007 and 168,790, having numerous improvements and advantages thereover, as will hereinafter become apparent.

A further object of this invention is to provide a cigarette holder and maker having but two relatively movable parts and which in the preferred form only a single continuous motion is necessary in completing the making of the cigarette and placing the device in cigarette smoking position.

A further object of this invention is to provide a cigarette maker and holder in which the made cigarette is held in position therein for smoking, yet the tobacco therein is automatically spaced from the end of the holder thereby insuring that the tobacco will not clog the holder and prevent free passage of the smoke therethrough, and at the same time it provides against any waste of the tobacco, for all the tobacco can be smoked down to the very end thereof, eliminating the usual wasted cigarette stub and leaving only a small end of the cigarette paper which is easily discarded, making the device ready for manufacturing and smoking another cigarette.

A further object of this invention is to provide a cigarette holder and maker which can be carried in the pocket and occupy no more space than the usual cigarette holder, which can be used to hold the completed cigarette at a greater or less a distance from the mouth as desired.

A further object of this invention is to provide a cigarette maker and holder in which the cigarette is made by the holder in cooperation with the tobacco container and thus is easily portable in the pocket of the user.

A further object of this invention is to provide a cigarette maker and holder in which the length of the tobacco portion of the cigarette may be predetermined by suitable placement of the cigarette paper on the holder, yet will permit smoking of the full length of the tobacco in the cigarette without any waste.

A further object of this invention is to provide a cigarette holder and maker which can be used to make cigarettes for use independent of the holder and, likewise, may be used for holding cigarettes already made by any other device.

Still a further object of this invention is to provide a cigarette holder and maker in which the cigarette paper of the cigarette will be held firmly in position on the end of the holder against

accidental falling off, yet will hold the tobacco of the cigarette spaced a slight distance from the edge of the holder to insure against the holder being clogged by tobacco particles.

With the foregoing and other objects in view this invention comprises combinations, constructions and arrangements of parts hereinafter set forth, disclosed, claimed and illustrated on the accompanying drawing wherein:

Fig. 1 is an elevational view of the two parts of the cigarette holder and maker in disassembled position;

Fig. 2 is a partly sectional and partly elevational view of the cigarette holder and maker ready to discharge the tobacco into the cigarette paper cylinder;

Fig. 3 is a sectional view on line 3—3 of Fig. 2;

Fig. 4 is an elevational view of the device in cigarette holding position, with the cigarette in section, and—

Fig. 5 is an elevational view of a modified form of this invention.

There is shown at 10 the cigarette maker and holder of this invention in the preferred form. This holder and maker 10 comprises a piston 11 having one end thereof closed off by an apertured piston head 12 provided with a plurality of smoke passages 13 therethrough. The other end of the piston 11 has a mouthpiece 14 secured thereto as at 15 in any suitable cooperative manner. 30 The piston 11 is hollow as at 16 and connects the apertures 13 to the usual aperture through the mouthpiece 14. The piston 11 may be filled with suitable smoke filter material 18, such as cotton or other material suitably treated if desired to absorb nicotine or moisture and filter the smoke on its way from the smoke passages 13 to the mouthpiece 14.

The outer surface of the piston 11 is provided with an elongated S or spiral-shaped groove 19 having a reverse curve 20 at the mouthpiece end and 21 at the piston head end. A thin sleeve or cylinder 22 having an internal diameter substantially equal to or infinitesimally larger than the external diameter of the piston 11 is provided to fit snugly over the piston 11. One end of the cylinder or sleeve 22 may be provided with a reinforcing collar 23. A radial threaded aperture 24 is provided through the collar 23 and the end of the sleeve 22 to receive a stud screw 25 there-through whose key extends into the spiral or S-shaped slot 19 in piston 11. The sleeve 22 is shorter than the piston 21 by about a thirty-second of an inch more or less, as shown in Fig. 1. The outer end of the sleeve 22 has its outer 55

diameter slightly increased by approximately one sixty-fourth of an inch more or less to provide a flared end, as at 26. Adjacent the end of the flared end 26 the sleeve 22 is provided with several circumferential markings 27, 28 and 29.

In operation the cigarette holder and maker 10 may be carried in the pocket in the assembled telescoped position without the cigarette thereon shown in Fig. 4. In order to make a cigarette 10 the sleeve 22 is rotated about the piston 11 causing it to travel to the other end thereof and be locked at the end of its travel against longitudinal reverse movement by the reverser 21 in the spiral groove 19. In this position the device 15 is tapped into a can or pouch of tobacco causing tobacco to enter the inside of the sleeve or cylinder 22 until it substantially fills this space up against the piston head 12. Several firm tapping motions will be sufficient to place a supply of 20 tobacco into the sleeve 22 which may then be forced against the piston head 12 at the other end of the sleeve 22 by pressing the end of a pencil thereagainst.

This operation may be repeated several times 25 if necessary until the sleeve 22 is full of tobacco as shown at 30. A prepared cigarette paper gummed at one longitudinal edge, if desired, is then wrapped around the outer side of the sleeve 22, the cigarette paper cylinder being completed 30 by licking or wetting the longitudinal edge and pressing it firmly over the adjoining edge in the customary manner. After being thus formed it is slid over the flared end 26 until the edge 31 of the cigarette paper cylinder 32 is in approximate alignment with any one of the circumferential markings 27, 28 or 29 according to the length of the cigarette desired.

To complete the cigarette the sleeve 22 is then rotated in a reverse direction about the piston 11 40 causing the piston 11 to press the piston head 12 against the tobacco 30 and force it into the cigarette paper cylinder 32 thus completing the cigarette. As the cylinder 22 is thus rotated to telescope it onto the piston 11 the key of screw 45 24 following the groove 19 enters the reverse curve 20, thus causing the sleeve 22 to move away a distance of approximately one thirty-second of an inch, thereby automatically spacing the tobacco 30 in the cigarette paper cylinder 32 an equal distance from the piston head 12 and smoke 50 passages 13 therein, thereby insuring that the tobacco 30 will not clog the smoke passageways. The cigarette as thus made is already in position on the holder for smoking.

If the user prefers the cigarette at a greater 55 distance from his mouth, he may merely reverse the rotation of the sleeve 22 on the piston 11 to then lock the sleeve 22 in extended position in the reverse curve 21. A cigarette of different 60 length may be made by stopping the edge 31 of the cigarette paper cylinder 32 at any desired 65 position along the outside of sleeve 22, any surplus tobacco within the sleeve 22 being discharged back into the tobacco can or pouch through the end of the cigarette paper cylinder 32.

As will be apparent the cigarette made by this device will be as firm as the conventional cigarette bought in packages. If the user does not 70 desire to smoke the cigarette in the holder provided hereby, it may easily be removed therefrom and smoked in the conventional manner, in which case, if desired, the other end of the cigarette may be placed in the mouth and the edge 75 31 of the cigarette paper cylinder 32 projecting

beyond the tobacco 30 will be burnt off in the very act of lighting the cigarette. On the other hand, a preformed cigarette such as bought in a package, may be smoked on this holder by merely pressing the end thereof into the flared edge 26 of the cylinder 22 while it is left in extended position. Due to the placing of such preformed cigarette in the end of the sleeve, or the position of the edge 31 of the cigarette paper cylinder 32 over the flared end of sleeve 22, no 10 air can creep in from the side but all of it must come through the burning end of the cigarette when it is lighted.

A modified form of this invention is shown at 40 in Fig. 5, the sleeve 41 thereof being substantially identical with the sleeve 22 of the preferred form, but in this case the piston 42 is provided with a straight longitudinal groove 43 terminating into circumferential grooves 44 and 45 for locking the sleeve 41 at either end thereof. 20

In the preferred form at 10 only a single rotary motion is necessary to extend or telescope the sleeve on the piston, while in the modified form 40 three motions are necessary, first a rotary motion, then a longitudinal motion, and 25 then a rotary motion. Otherwise the construction and operation of this modified form 40 is substantially identical with that of the preferred form at 10.

From the above description it will be seen that 30 there has been disclosed a cigarette maker and holder well adapted for its intended function, as will be obvious to those skilled in the art. Various other changes and modifications may be made to embody the spirit and purpose of this 35 invention, and it is contemplated to cover such variations and to be limited in this respect as may be necessary by the scope of what is hereinafter claimed.

Having thus set forth and disclosed the invention 40 what is claimed is:

1. A combination cigarette maker and holder comprising a hollow piston, an apertured piston head at one end thereof, a cylindrical sleeve adapted to telescope over said piston, and co-operating means on one end of said sleeve and 45 in said piston limiting and guiding the telescopic action of said sleeve over said piston, said co-operating means comprising a key extending through said sleeve, and a groove along the outer side of said piston into which groove said key extends, said groove being of longitudinal S-shape, the reverse portions of said S-shape groove providing means for locking said sleeve in telescoped or extended position. 50

2. A combination cigarette maker and holder comprising a hollow piston, an apertured piston head at one end thereof, a cylindrical sleeve adapted to telescope over said piston, and co-operating means on one end of said sleeve and 60 in said piston limiting and guiding the telescopic action of said sleeve over said piston, said co-operating means comprising a longitudinally extending groove on the outer surface of said piston, a circumferentially extending groove at 65 each end of said longitudinally extending groove, and a cooperating key extending through said sleeve into said groove for guiding and limiting the movement of said sleeve on said cylinder.

3. A combination cigarette maker and holder 70 comprising a hollow piston, an apertured piston head at one end thereof, a cylindrical sleeve adapted to telescope over said piston, and co-operating means on one end of said sleeve and 75 in said piston limiting and guiding the telescopic

action of said sleeve over said piston, said sleeve being of thin material to receive a cigarette paper rolled thereabout, the other end of said sleeve being slightly flared to hold the cigarette paper cylinder rolled thereabout from accidentally sliding beyond a predetermined amount.

5. A combination cigarette maker and holder comprising a hollow piston, an apertured piston head at one end thereof, a cylindrical sleeve adapted to telescope over said piston, and cooperating means on one end of said sleeve and in said piston limiting and guiding the telescopic action of said sleeve over said piston, said sleeve being of thin material to receive a cigarette paper rolled thereabout, the other end of said sleeve being slightly flared to hold the cigarette paper cylinder rolled thereabout from accidentally sliding beyond a predetermined amount, said

cooperating means comprising a key extending through said sleeve, and a groove along the outer side of said piston into which groove said key extends, said groove being of longitudinal S-shape, the reverse portions of said S-shape 5 groove providing means for locking said sleeve in telescoped or extended position, the cigarette being formed by filling the sleeve with tobacco in extended position, by rolling the cigarette paper about said sleeve and sliding it over the 10 flared end to the predetermined position and then telescoping the plunger within said sleeve by relatively rotating the plunger and sleeve until the sleeve is in locked telescopic position relative to the plunger, and the tobacco being automatically spaced from the piston head to prevent 15 clogging of the smoke passages therethrough.

MAX FRIEDMAN.
